UNITED STATES PATENT OFFICE.

GUSTAVUS H. HERMANN, OF MINNEAPOLIS, MINNESOTA.

GAS-BURNER APPLIANCE.

1,144,199.

Specification of Letters Patent. Patented June 22, 1915.

Application filed November 24, 1914. Serial No. 873,749.

To all whom it may concern:

Be it known that I, GUSTAVUS H. HERMANN, a citizen of the United States, residing at Minneapolis, in the county of Hennepin and State of Minnesota, have invented certain new and useful Improvements in Gas-Burner Appliances, of which the following is a specification.

This invention relates to gas burners.

10 One object is to provide a gas burner particularly adapted for application to an ordinary range or stove to facilitate baking in the oven thereof and which may be instantly removed when desired and the stove or 15 range used to bake by coal, wood or other fuel.

Another object resides in the provision of a gas burner which may be readily applied or positioned in an oven of an ordinary 20 range or stove obviating the necessity of providing a specially constructed stove and without the necessity of cutting into the flues of the stove and thereby impairing the baking quality when the gas burner is removed and wood, coal or other fuel used for 25 baking purposes.

With the above and other objects in view, the present invention consists in the combination and arrangement of parts hereinafter 30 more fully described, illustrated in the accompanying drawings, and particularly pointed out in the appended claims, it being understood that changes may be made in the form, proportion, size and minor details 35 without departing from the spirit or sacrificing any of the advantages of the invention.

In the drawings: Figure 1 is a horizontal sectional view through a stove illustrating 40 the present invention. Fig. 2 is a vertical sectional view, and Fig. 3 is a detail view of the burner including the air flue.

Referring now more particularly to the accompanying drawings, the reference character 5 indicates a gas, wood, coal or other stove including upper and lower air flues 6 and 7, respectively, an oven 8, and a top 9, access being had to the oven 8 by way of a door 10 at the front, as usual. In the oven 8 45 there is illustrated the usual shelf 11 composed of wire or other suitable material and to which a non-conducting deflecting plate 12 may be secured to properly distribute the heat in the oven when applied through the 50 instrumentality of my improved burner attachment.

The character 13 indicates an air duct which may be of any shape in cross section, that is to say, it may be round, oval or square, but is preferably rectangular, as 60 shown. This duct 13 preferably has a longitudinal opening 14 in its top which extends throughout its length. The air duct 13 is preferably positioned on the bottom of the oven by insertion through an opening 65 15 in the rear wall of the stove 5, there being a weighted door 16 secured to the rear wall of the stove 5 which moves normally to closed position to close the opening 15 when my improved burner attachment is withdrawn from the oven. The outer end of the air duct 13 is open and when used has its outer open end preferably positioned flush with the opening 15 or projecting slightly therefrom. The inner end of the air duct 70 13 is preferably closed with its rear wall provided with a substantially semicircular recess 17 adapted to receive the inner end of the burner 18 which latter is suspended within the air duct 13 through the aforesaid 75 longitudinal opening slightly spaced from the edges of the latter, and supported in this position by means of straps or other supporting elements 19 and 20 which may be secured in any suitable manner to the burner 80 18 and also to the top of the air duct 13 on opposite sides of the opening 14, as clearly shown in the drawings. The air duct 13 and the burner 18 are preferably disposed immediately beneath the aforesaid deflector 12 so 85 that the heat may be properly distributed in the oven.

It is clear from the foregoing description that the air duct 13 and the burner 18 may be secured together prior to insertion in the 90 oven and that when connected together the same may be readily positioned within the oven beneath said deflector.

The burner 18 has a plurality of apertures on opposite sides thereof which are preferably slightly above the top of the air duct 13. The burner is preferably slightly spaced 95 from the edges of the opening 14 as before stated, whereby the air is brought into direct contact with the flames from the burner. 100 By virtue of this arrangement it will simply require enough air to keep the flames at their points of highest efficiency and therefore the air entering the outer end of the duct 13 and passing upwardly around the 105 burner through the spaces between the latter and the sides of the opening 14 will not have

a tendency to cool the oven. The inner end of the burner 18 is of course closed and the burner and air duct are so positioned that the outer end of the burner may have a close fit against the mixing device 21.

22 is an ordinary gas valve which has connection with a pipe 23 leading from the main gas supply and this valve 22 may be readily operated in any suitable manner for 10 the supply of gas, one means being to provide the valve with a long stem 24 which may pass upwardly through the top 9 and be rotated in any suitable manner to operate the valve as, for instance, by means of a 15 hand lever or the like 24.

What I claim as new and desire to protect by Letters Patent is:—

1. The combination of a cooking stove or range including an oven and provided with 20 an opening in one side adjacent the upper surface of the bottom, an air duct supported directly on the bottom of the oven and having an unrestricted opening at its outer end, the open outer end of the duct lying within 25 said opening in the side wall of the stove or range, the duct also having a longitudinal opening in its top which extends throughout the length thereof, and a gas tube suspended partly within said duct through the 30 longitudinal opening in the top of the duct and at its outer end projecting through the unrestricted opening at the outer end of the duct and also projecting through the said opening in the side wall of the stove or 35 range.

2. The combination of a cooking stove or range including an oven and an opening in one side wall thereof leading into the oven at the bottom of the latter, an air duct supported 40 on the bottom of the oven and having communication with the atmosphere through the opening in the side wall of the stove or range and provided with a longitudinal opening in its top, and a gas tube supported 45 in the longitudinal opening of the air duct in spaced relation to the edges of said longitudinal opening and having perforations on opposite sides thereof slightly above the top of said duct, said gas tube extending 50 beyond the outer end of the duct and projecting through said opening in the side wall of the stove or range.

3. The combination of a cooking stove or range including an oven and an opening 55 formed therein adjacent the bottom of the oven, an air duct removably inserted through said opening and disposed on the bottom of the oven and having communication with the atmosphere through said opening, the duct having a longitudinal opening in its 60 top, the inner end of the duct being semi-circular providing a seat, and a gas tube lo-

cated in said longitudinal opening and at its inner end disposed on the seat of the duct with its outer end projecting through the 65 outer end of the duct and through the opening adjacent the bottom of the oven, said tube being spaced slightly from the edges of said opening and having openings in opposite sides slightly above the top of the air 70 duct and adjacent the spaces between the tube and the edges of said opening in the top of the air duct.

4. A gas appliance of the character described comprising an air duct provided 75 with a longitudinal opening in its top, the duct being closed at one end and having an unrestricted opening at its outer end, a gas tube disposed in said longitudinal opening 80 of the duct and extending through the unrestricted opening of the latter, and means to secure the gas tube in the longitudinal opening of the duct, the tube being spaced slightly from the edges of said longitudinal opening and having openings at opposite 85 sides slightly above the longitudinal opening of the duct whereby the air is fed from the duct to the flame at short range.

5. The combination of a cooking stove or range including an oven and having an opening 90 in its side adjacent the bottom of the oven, an air duct removably supported directly on the bottom of the oven and having communication with the atmosphere only through said opening in the side of the 95 stove or range, the bottom of the oven being imperforate, said air duct having a longitudinal opening in its top, and a gas tube mounted in said longitudinal opening of the duct and provided with apertures adjacent 100 the sides of the longitudinal opening.

6. A gas appliance of the character described, comprising an air duct which is substantially rectangular in cross section and which is closed at one end and which has an 105 unrestricted opening at its other end of a width equal to the width of the duct, the air duct also having a longitudinal opening formed in its upper side and which extends throughout the length thereof, a gas tube 110 projecting partly within and partly without the air duct through the longitudinal opening and having a closed end, the gas tube being spaced slightly from the edges of said longitudinal opening and having 115 apertures therein on opposite sides thereof slightly above the edges of said opening.

In testimony whereof I affix my signature in presence of two witnesses.

GUSTAVUS H. HERMANN.
